DESIGN FOR A DOG STATUETTE

Sydney R. Carr, Palo Alto, Calif.

Application September 13, 1944, Serial No. 115,294

Term of patent 3½ years

(Cl. D29—23)

To all whom it may concern:

Be it known that I, Sydney R. Carr, a citizen of the United States, residing at Palo Alto, in the county of Santa Clara and State of California, have invented a new, original, and ornamental Design for a Dog Statuette, of which the following is a specification, reference being had to the accompanying drawing, forming part thereof.

I claim:

The ornamental design for a dog statuette, as shown.

SYDNEY R. CARR.
